CLAIM

The ornamental design for a cellular phone case, as shown and described.

DESCRIPTION

FIG. 1 is a front perspective view of a cellular phone case showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof showing the cellular phone case in an open configuration and showing the interior thereof.
